UNITED STATES PATENT OFFICE.

WILLIAM F. KIESEL, JR., OF ALTOONA, PENNSYLVANIA.

MEANS FOR SUPPLYING LIVE BLOWER STEAM AND SMOKE-LIFTER STEAM IN LOCOMOTIVES.

Application filed February 4, 1920. Serial No. 353,263.

To all whom it may concern:

Be it known that I, WILLIAM F. KIESEL, Jr., a citizen of the United States, and a resident of Altoona, Blair County, State of Pennsylvania, have invented certain new and useful Improvements in Means for Supplying Live Blower Steam and Smoke-Lifter Steam in Locomotives, of which the following is a specification.

10 The present invention relates to locomotives and more particularly to the means for supplying the live blower steam and smoke lifter steam. Heretofore the live blower steam and smoke lifter steam have been controlled by valves in the cab, thus requiring steam pipes extending from the cab to the front of the locomotive. As these pipes are located on the outside of the locomotive there is considerable condensation therein. The 15 aim of the present invention is to eliminate this condensation by doing away with the pipes on the outside of the locomotive. It is a further object to relieve to some extent the congestion of pipes and valves in the cab.

20 To these ends the invention consists of a blower or smoke lifter valve in the smoke box or at the front of the locomotive and means for controlling said valve from the cab. Furthermore the steam supply pipe to 25 said valves is disposed within the boiler shell where it is kept at a relatively high temperature, thus eliminating condensation.

Other objects and features of novelty will be apparent from the description taken in 30 connection with the drawings, in which:

Figure 1 is a plan view of a blower and smoke lifter valves and associated parts and the means for operating the same, the outline of the boiler being shown in dot and dash 35 lines;

Figure 2 is a side elevation of the parts shown in Fig. 1;

Figure 3 is an end elevation of the parts shown in Fig. 1;

40 Figure 4 is a side elevation of the blower valve and the operating quadrant;

Figure 5 is a sectional elevation taken substantially on the line 5—5 of Figure 4;

Figure 6 is a sectional elevation taken substantially on the line 6—6 of Figure 5;

Figure 7 is a sectional elevation taken substantially on the line 7—7 of Figure 6;

Figure 8 is a partial sectional elevation corresponding to Figure 5 through the 55 smoke lifter valve;

Figure 9 is a top plan view of the operating mechanism for the valve disposed in the cab;

Figure 10 is a side elevation of the parts shown in Figure 9; and

Figure 11 is a sectional elevation taken substantially on the line 11—11 of Figure 10.

Referring to the drawings the reference numeral 20 indicates the steam pipe leading from the steam dome of the boiler through 60 the front head 21 into the smoke box 22. A pipe 23 leads from the pipe 20 to a blower valve 24 which is adapted to control the supply of steam to the blower nozzles 25, disposed under the stack of the locomotive. In 65 the form of the invention shown the stack is divided into four parts and there are a plurality of nozzles 25 discharging into different parts of the stack. Leading from the pipe 23 is a pipe 26 conveying steam to a smoke lifter 70 valve 27, this valve being adapted to control the supply of steam to the pipe 28 which leads to the top of the stack and provides 75 live steam for lifting the smoke in the usual manner.

According to the present invention the blower and smoke lifter valves 24 and 27 are disposed within the smoke box of the locomotive and have parts projecting outside of the shell of the boiler so that the 80 valves may be operated from the cab of the locomotive.

Referring to Figures 4 to 7 inclusive it will be seen that the blower valve comprises a body 29 secured to the shell 30 of 85 the boiler or the interior thereof by means of bolts 31. The steam pipe 23 is connected to the flange 32 of the valve body and communicates with the inlet chamber 33. The chamber 33 may have communication with an outlet chamber 34 through suitable passages 35 controlled by the valve disk 36. The outlet chamber 34 has communication with the steam nozzles 25 through the pipe 37. A connection 38 extending through an aperture 39 in the shell is provided so that a steam hose may be secured to the same for the purpose of 90 furnishing steam to create a draft if the locomotive is in the round house and is getting up steam. A valve bonnet 40 extends through an aperture 41 in the boiler shell and into the body of the valve, this bonnet 95 preferably being held in position by the said bolts 31 and being removable from the valve 100 105 110

body from the outside of the shell without in any way requiring dismounting of the said body. Outside the shell the bonnet is provided with a housing or casing portion 42 which has an opening in its opposite sides as at 43 and 44, (Figure 6). The valve stem comprises two portions, an inner part 45 and an outer part 46. At its inner end the part 45 has a projection and slot 10 connection with the valve disk 36 so that when the stem is rotated the disk is also turned with it, but the bonnet together with the stem may be withdrawn from the body without disturbing the disk. At its outer 15 end the part 45 has a square head 47 disposed in a corresponding recess in the inner end of the part 46, the outer end of this latter part having a quadrant arm 48 secured thereto in any suitable manner. The 20 swinging of the arm 48 will therefore turn the disk 36 and open or close the valve. In the present instance, spring means is provided to turn the valve in one direction and a connection is made to the arm 48 to turn it 25 in the other. As shown the part 46 of the valve stem has a pair of spaced arms 49 secured thereto the said arms being disposed within the housing 42. A pin 50 is carried by the housing and a link 52 slotted 30 throughout the greater part of its length is disposed with the pin 50 in the slot intermediate its ends one end of the link being connected by a pin 53 with the arms 49 and the other end connected by means of a pin 35 54 to a spring abutment 55. A second spring abutment 56 is pivotally mounted on the pin 50 and a compression spring 57 is interposed between said abutments. As a result the spring acts through the link 52 and 40 arms 49 to turn the valve stem in one direction, that is, in the closing direction. The valve is opened of course by turning the arm 48 in the opposite direction. One feature of the spring arrangement for closing the valve described above, is that the varying or increased 45 force of the spring as it is compressed is exerted on the stem as a substantially uniform resistance. This will be apparent from a study of Figure 6 of the drawings. When 50 the arms 49 turn to the right as viewed in said figure the axis of pin 53 describes an arc of a circle. The axis of pin 50 however is fixed so that the outer spring abutment 55 through the link 52 will be moved upwardly as viewed in said figure. Hence the 55 geometrical arm from the axis of the stem to the line of action of the spring decreases as the valve is opened and of course this means that the force resisting opening of 60 the valve does not increase with the compression of the spring.

The smoke lifter valve 27 is like the blower valve just described except that its body 29' does not have a connection for the 65 steam hose. Steam is supplied through a

pipe 26 to the inlet chamber 33, communication with the outlet chamber 34' being controlled by the valve disk 36, said outlet chamber 34' being connected to the pipe 28 which extends to the top of the stack.

As previously stated, according to the present invention, these valves are operated and controlled from the cab of the locomotive. To this end a flexible connector 58 is secured to the quadrant arm 48 and extends to the cab so that when said connector is pulled the valve will be opened against the opposition of the spring. A similar flexible connector 59 extends from the cab to the quadrant arm 60 of the smoke lifter 80 valve so that this valve is operated in the same manner as the blower valve. Preferably the connectors 58 and 59 are disposed in the hand rail 61 on the side of the locomotive.

Any suitable means may be disposed within the cab of the locomotive for actuating the connectors 58 and 59. According to the present invention however a bar 62 I-shaped in cross section is secured at its front end to a front wall 63 of the cab, in any suitable manner as the bolt connections 64, said bar being disposed horizontally. A bracket arm 65 carried by the cab is secured to the bar so as to steady the same. The bottom edges 95 of the flanges of the bar are serrated as at 66, while the opposite upper edges of the flanges are smooth. A pair of handles are provided each having a hooked upper end 67 slidable on a smooth edge of a flange 100 and also rockable to carry the tooth 68 into and out of engagement with one of the serrations 66, a suitable hand grip 69 being provided to manipulate the handle.

One of these handles is slidable on a 105 flange at one side of the bar and a second handle is slidable on the opposite flange. The connector 58 is secured to an arm 70 on one of the handles and the connector 59 to a similar arm on the other.

Normally the two valves are closed and when it is desired to open one or the other, the proper handle 69 is gripped and turned in a direction to free its tooth 68 from the serrations and is then slid along the I bar 115 to the right as viewed in Figure 10. Through the flexible connector this will turn the stem of the valve against the opposition of the valve spring in a direction to open the valve. When the valve has been opened 120 to the desired amount, on letting go of the operating handle, the pull on the same will automatically turn it in a direction to throw its tooth 68 into engagement with one of the serrations, thus holding the valve at any 125 desired degree of opening.

Although the invention has been described in connection with a specific embodiment thereof it is to be understood that it is not thus limited but includes modifications and 130

changes which come within the scope of the appended claims.

Having thus described the invention what is claimed as new and desired to be secured 5 by Letters Patent is:

1. In a locomotive, a pipe to supply steam to the stack adjacent its upper periphery, a valve in said pipe adjacent the stack, and means to effect operation of said valve from 10 the cab.

2. In a locomotive, a smoke lifter controlling valve adjacent the stack, and means to operate said valve from the cab of the locomotive.

3. In a locomotive, a blower controlling valve secured to the boiler shell adjacent the stack, and means to operate said valve from the cab of the locomotive.

4. In a locomotive, a blower controlling 20 valve secured to the boiler shell within the smoke box, and means to effect operation of said valve from the cab.

5. In a locomotive, a valve secured to the boiler shell on the inferior and at the 25 front end thereof, and means to effect operation of said valve from the cab.

6. In a locomotive, a valve secured to the boiler shell within the smoke box having its stem extending outside the shell, an actuator in the cab, and means operatively connecting said actuator and stem, whereby the valve may be controlled from the cab.

7. In a locomotive, a valve mounted within the boiler shell at the smoke box end having its stem extending outside the shell, a quadrant secured to the stem, yieldable means acting to oppose opening of the valve, and a flexible connector extending from the quadrant to the cab.

8. In a locomotive, a valve mounted within the boiler shell at the smoke box end having its stem extending outside the shell, a hollow hand rail on the side of the locomotive, and means to effect operation of said 45 valve from the cab including a flexible connection extending from the cab through said rail to the valve.

9. In a locomotive, a valve mounted within the boiler shell at the smoke box end having its stem extending outside the shell, a hollow hand rail on the side of the locomotive, an arm on said stem, yielding means acting to oppose opening of the valve, and a flexible connection extending from the 55 cab through said rail to said arm.

10. In a locomotive, a blower valve, a smoke lifter valve, both said valves being at the front of the boiler, a hollow hand rail on the side of the boiler, and means extending from the cab through said rail to said valves for operating the same.

11. In a locomotive, a blower valve, a smoke lifter valve, both said valves being at the front of the boiler within the boiler 65 shell and having stems projecting outside

said shell, arms on said stems, a tube on the side of the boiler, and flexible connectors extending from the cab through said tube to said arms for operating the valves.

12. In a locomotive, a valve in the smoke 70 box within the boiler shell having a stem extending outside the shell, an arm on said stem, a connector extending from said arm to the cab, and a spring acting to close said valve.

13. In a locomotive, a valve in the smoke 75 box within the boiler shell having a stem extending outside the shell, an arm on said stem, a connector extending from said arm to the cab, and a spring acting to oppose 80 turning of said stem in one direction.

14. In a locomotive, a valve at the front of the boiler, a bar within the cab, a member 85 slideable on said bar, a connection from the member to the valve for actuating the valve by movement of said member, and means to hold the member in any one of a plurality of positions along said bar.

15. In a locomotive, a valve at the front of the boiler, a bar within the cab having 90 serrations in an edge thereof, a member slideable along said bar having a tooth engaging a serration, said member also being rockable to disengage said tooth from a serration and move it to engage another serration, and a connection from the member to the valve for actuating the valve by the sliding movement of said member.

16. In a locomotive, means for actuating a valve in front of the cab, including a bar 100 in the cab having a smooth edge and an opposite serrated edge, and a handle having a hook slideable and rockable on said smooth edge, said handle having a tooth adapted by rocking the handle to be moved into and out of engagement with said serrations.

17. In a locomotive, means for actuating a pair of valves located in front of the cab, including an I-bar having one edge of each flange serrated, a pair of handles each having a hook slideable and rockable on the smooth edge of the flange, and each having a tooth adapted by rocking the handle to be moved into and out of engagement with said serrations.

18. In a locomotive, a valve adjacent the front end of the boiler, a spring acting to close said valve and a ratchet device in the cab connected to the valve to open the same in opposition to the spring.

19. In a locomotive, a valve body secured to the shell on the inside thereof, said shell having an opening, a removable valve bonnet extending through said opening into the body, means on the outside of the boiler 125 shell securing the bonnet in the body, and a valve stem carried by and extending through said bonnet to the exterior of the boiler.

20. In a locomotive, a blower nozzle adapted to discharge into the stack, a steam 130

pipe within the boiler shell extending from the steam dome directly to said nozzle, a valve in said pipe, said valve secured to the smoke box shell and having a stem extending outside the shell, and means for operating said valve from the cab.

21. In a locomotive, a blower valve secured to the boiler shell on the interior and at the front end thereof, and means to effect 10 operation of said valve from the cab.

22. In a locomotive, a blower valve secured to the boiler shell within the smoke box having its stem extending outside the shell, an actuator in the cab, and means operatively connecting said actuator and stem, whereby the valve may be controlled from the cab.

23. In a locomotive, a blower valve mounted within the boiler shell at the smoke box end having its stem extending outside the shell, a quadrant secured to the stem, yieldable means acting to oppose opening of the valve, and a flexible connector extending from the quadrant to the cab.

25. 24. In a locomotive, a blower valve mounted within the boiler shell at the smoke box end having its stem extending outside the shell, a hollow hand rail on the side of the locomotive, and means to effect operation 30 of said valve from the cab including a flexible connection extending from the cab through said rail to the valve.

25. In a locomotive, a blower valve mounted within the boiler shell at the smoke box end having its stem extending outside the shell, a hollow hand rail on the side of the locomotive, an arm on said stem, yielding means acting to oppose opening of the valve, and a flexible connection extending 40 from the cab through said rail to said arm.

26. In a locomotive, a smoke lifter valve in the smoke box within the boiler shell having a stem extending outside the shell, an arm on said stem, a connector extending 45 from said arm to the cab, and a spring acting to close said valve.

27. In a locomotive, a smoke lifter valve in the smoke box within the boiler shell having a stem extending outside the shell, an 50 arm on said stem, a connector extending from said arm to the cab, and a spring acting to oppose turning of said stem in one direction.

28. In a locomotive, a smoke lifter valve at the front of the boiler, a bar within the 55 cab, a member slideable on said bar, a connection from the member to the valve for actuating the valve by movement of said member, and means to hold the member in any one of a plurality of positions along 60 said bar.

29. In a locomotive, a smoke lifter valve at the front of the boiler, a bar within the cab having serrations in an edge thereof, a member slideable along said bar having a 65 tooth engaging a serration, said member also being rockable to disengage said tooth from a serration and move it to engage another serration, and a connection from the member to the valve for actuating the valve by 70 the sliding movement of said member.

30. In a locomotive, a smoke lifter valve adjacent the front end of the boiler, a spring acting to close said valve and a ratchet device in the cab connected to the valve to 75 open the same in opposition to the spring.

31. In a locomotive, a smoke lifter valve body secured to the shell on the inside thereof, said shell having an opening, a removable valve bonnet extending through said 80 opening into the body, means on the outside of the boiler shell securing the bonnet in the body, and a valve stem carried by and extending through said bonnet to the exterior of the boiler.

32. In a locomotive, a valve in front of the cab and means to actuate said valve including a bar in the cab having a smooth edge and an opposite serrated edge, and a handle having a hook slideable and rockable 90 on said smooth edge, said handle having a tooth adapted by rocking the handle to be moved into and out of engagement with said serrations.

33. In a locomotive, a pair of valves located in front of the cab and means for actuating said valves including an I-bar having one edge of each flange serrated, a pair of handles each having a hook slideable and rockable on the smooth edge of the flange, 100 and each having a tooth adapted by rocking the handle to be moved into and out of engagement with said serrations.

In testimony whereof I affix my signature.

WILLIAM F. KIESEL, JR.
